P.C.(57) **CLAIM**

The ornamental design for a light emitting diode filament, as shown and described.

DESCRIPTION

FIG. 1 is a perspective view of a light emitting diode filament showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line portions of the light emitting diode filament in FIGS. 1-7 represent unclaimed portions of the design and form no part thereof.
